UNITED STATES PATENT OFFICE.

MELVIN PERDUE AND WILLIAM A. SHAW, OF SHELBY, OHIO.

BALL-COUNTING MACHINE.

Application filed February 18, 1920. Serial No. 359,577.

To all whom it may concern:

Be it known that we, MELVIN PERDUE and WILLIAM A. SHAW, citizens of the United States, residing at Shelby, in the county of 5 Richland and State of Ohio, have invented certain new and useful Improvements in Ball-Counting Machines, of which the following is a specification.

This invention relates to ball counting machines, such as are used for counting out 10 definite numbers of balls for packaging the same.

The object of the invention is to provide an improved machine of this kind which insures 15 accuracy in counting of the balls, which enables the balls to be rapidly counted and packaged, and which machine is of simple construction, can be made at low cost, is easy to operate and can be readily taken 20 apart for repairs or for other purposes.

Further objects of the invention are in part obvious and in part will appear more in detail hereinafter.

The invention comprises the construction 25 and arrangement of parts hereinafter described and claimed.

In the drawings, Fig. 1 illustrates a sectional elevation on substantially the line 1-1, Fig. 4, of one preferred embodiment 30 of the invention; Fig. 2 is a cross section on the line 2-2, Fig. 1; Fig. 3 is a front elevation; Fig. 4 is a side elevation from the right in Fig. 3; and Fig. 5 is a sectional plan view on the line 5-5, Fig. 2.

The counting machine shown in the drawings comprises a suitable frame preferably formed in two parts for convenience in assembling and in taking the machine apart for repairs. This frame comprises a base 35 1 of suitable form upon which is supported an upper member 2, the upper portion of which is formed as a hopper 3 of any size or dimensions to contain the balls or other articles to be counted. These two members 40 1 and 2 are detachably connected in any suitable manner, such as by providing the lower member with a peripheral seat 4 to receive the lower edge of the member 2, the two members being secured by screws 5 passing 45 through ears 6 on member 1 into openings in member 2. The walls of member 2 slope downwardly toward the center and its bottom consists of sloping floor plates 7 which are inclined downwardly toward the center. 50 Base 1 is provided with a delivery table 8 which forms the bottom of a tapering or

converging spout 9 through which the counted balls are delivered into any suitable receptacle, such as the box 10.

The counting mechanism comprises a 60 shaft 11 reduced at its opposite ends to receive bearing members 12 lying in openings in the adjoining edges of the upper and lower frame members and which are clamped between said edges. Consequently 65

the shaft turns in stationary bearings and by taking the two frame members apart said shaft and bearings and the other parts carried by the shaft can be readily taken out for inspection or repair. The outer 70 ends of the shafts extend beyond the bearings.

One end of the shaft is provided with a ratchet 13 cooperating with a pawl 14 pivoted at 15 to the frame and yieldingly held in engagement with the ratchet by a 75 tension spring 16. Ratchet 13 preferably has a fairly large number of teeth, say approximately ten, so as to prevent backward turning of the shaft in practically any position to which it may be adjusted. The 80 other end of the shaft is provided with a suitable stop device, such as the one-tooth ratchet 17, the single stop or tooth 18 of which co-operates with a yielding pawl 19. On one end of the shaft is an operating 85 handle 20.

Within the casing the shaft is provided with counting devices which consist of a series of annular members 21 each of which is provided with a continuous transverse 90 wall 22 perpendicular to the shaft 11 and a series of regularly spaced radially extending walls 23 parallel with and passing through the axis of said shaft. Each member is also provided with a cylindrical wall 95 24 which forms the bottoms of the several chambers 25 which are separated by the walls 23, and which cylindrical walls also serve to uniformly space the members 21 apart. Transverse walls 22 are preferably 100 also provided with curved teeth or projections 26, the curvature being backward in the direction of rotation which is represented by the arrow A, Fig. 2, and the edges of said projections being fairly sharp as indicated at 27, Fig. 1. A series of like members 21 are nested together side by side upon the shaft 11, the chambers in the last member being closed by a blank plate 28. Members 21 are secured together with their 110 radial walls 23 in alignment by one or more longitudinally extending rods 29 and are

also secured to rotate with shaft 11 in any suitable manner, such as by the cross pin 30. The counting device lies at the center of the bottom of the upper chamber in which the balls to be counted are contained, and the edges of the floor members 7 are preferably slotted out, as at 31, to receive the transverse walls 22 and are provided with tongues 32 which enter the spaces between the projections 26.

The apparatus may be used for counting any kind of like articles of spherical or other shape, especially where it is desired to package such articles with a definite number in a package. One example of such use is in packaging chewing gum which is frequently put up in the form of candy coated spheres, one hundred or some other number to a package. The present apparatus, as illustrated in the drawings, is designed for counting out one hundred balls for a package. Consequently the shaft 11 is provided with ten of the members 21, each having ten chambers or compartments 25. Fig. 4 represents the normal position of the parts, in which the pawl 19 engages the tooth 18. By releasing the pawl 19 the shaft 11 may be turned through one complete revolution until pawl 19 again engages the stop tooth 18. During said complete revolution each one of the compartments in turn enters the chamber in the upper part of the casing, receives its ball and carries the ball to and discharges it upon the table 8. In the discharging position the balls readily roll out of the compartments upon said table. One compartment can receive no more than a single ball and filling of all compartments is insured by the constant stirring action produced by the projections 26.

What we claim is:

1. Ball counting apparatus, comprising a container having walls converging to a bottom opening, a counting device closing said opening and comprising a rotary cylindrical member having a series of longitudinally and annularly extending walls forming ball receiving compartments, said annular walls having outward extensions forming stirring members.

2. Ball counting apparatus, comprising a container having walls converging to a bottom opening and provided with narrow slots adjacent said opening, a counting device closing said opening, said device comprising a cylindrical member rotatable in one direction only and having a series of longitudinally and circumferentially spaced ball receiving compartments, and stirring members carried by said device and distributed circumferentially around the same and passing through said narrow slots.

3. Ball counting apparatus, comprising a container having walls converging to a bottom opening, a counting device closing said opening, said device comprising a rotary cylindrical member having a series of longitudinally and circumferentially spaced ball receiving compartments, means at one end of said device for preventing reverse turning movement thereof, and releasable stop means at the other end of said device for normally preventing turning movement of said device in the discharging direction beyond a complete revolution. 75

4. Ball counting apparatus, comprising a container having walls converging to a bottom opening, a counting device closing said opening, said device comprising a shaft, and a series of like members nested together on said shaft, each of said members having a transverse wall and a series of radial walls and adapted with an adjacent member to form a series of circumferentially spaced compartments. 80

5. Ball counting apparatus, comprising a two membered frame divided on a horizontal plane, the upper member of said frame having walls converging to an opening near said plane, and a rotary counting device 90 journaled on a horizontal axis between the two members of said frame and closing said opening.

6. Ball counting apparatus, comprising a two membered frame divided on a horizontal plane, the upper member of said frame having walls converging to an opening near said plane, and a rotary counting device journaled on a horizontal axis between the two members of said frame and closing said 100 opening, said device having a series of longitudinally and circumferentially spaced ball receiving compartments and a single delivery spout carried by the lower frame member and arranged to receive all the balls 105 discharged by said device.

7. Ball counting apparatus, comprising a two membered frame divided on a horizontal plane, the upper member of said frame having walls converging to an opening near 110 said plane, a rotary counting device journaled between the two members of said frame and closing said opening, said device having a series of longitudinally and circumferentially spaced ball receiving compartments, means carried by the upper member for preventing reverse rotation of said device, and the lower member being provided with a delivery table upon which all of the balls are discharged by said device. 115
